UNITED STATES PATENT OFFICE.

EDWARD G. BUDD, OF PHILADELPHIA, PENNSYLVANIA, ASSIGNOR TO BUDD WHEEL COMPANY, OF PHILADELPHIA, PENNSYLVANIA, A CORPORATION OF PENNSYLVANIA.

PROCESS OF STRAIGHTENING TAPERED DISKS.

Application filed October 29, 1921. Serial No. 511,520.

To all whom it may concern:

Be it known that I, EDWARD G. BUDD, a citizen of the United States, residing at Philadelphia, Pennsylvania, have invented 5 certain new and useful Improvements in Processes of Straightening Tapered Disks, of which I declare the following to be a full, clear, and exact description.

This invention relates to a process of 10 straightening tapered disks.

In the rolling of tapered disks suitable for use in the manufacture of disk wheels for automobiles, I have found that the rolling operation frequently produces wrinkles or 15 buckles in the tapered disk which interfere with subsequent forming operations.

It is the object of my invention to provide a method of straightening such tapered disks in order to remove the wrinkles or buckles 20 so as to provide a perfectly uniform tapered blank which can be successfully operated on by dies.

Further objects, and objects relating to 25 details and economies of operation, will definitely appear from the detailed description to follow. I accomplish the objects of my invention by the devices and means illustrated in the accompanying drawing, forming a part of this specification. My invention 30 is clearly defined and pointed out in the appended claims.

In the drawings, Figure 1 is a diagrammatic, sectional view illustrating my method 35 of removing buckles from tapered disks.

Fig. 2 is a plan view of one of the disks 40 before being subjected to this process.

Fig. 3 is a plan view of the master-plate used in this process, and

Fig. 4 is a sectional view through a master-plate and two disks, showing the means 45 by which two disks may be subjected simultaneously to this straightening operation.

In the drawing, the same reference numerals refer to the same parts throughout the 50 several views.

I carry out my invention by providing a master-plate having a seat or recess or other surface configuration which is complementary in form to a perfect tapered disk.

The buckled disk is laid upon the master-plate and the two are passed through a series 55 of rolls. Sometimes a single pass in one direction will remove all the buckles but, at other times, it is desirable to pass the master-

plate and the buckled disk through the rolls 55 several times along different radii of the disk.

In the drawings, I have shown a disk, 10, which is illustrated as having a series of irregularly arranged buckles, 11. These 60 would interfere with the action of the dies in subsequent forming operations upon the disk and, therefore, it is necessary to remove these buckles. I accomplish this by providing a master-plate matrix, 12, which has a 65 conical depression or seat, 13, therein, complementary to the perfect disk, so that when a perfect disk is laid upon this master-plate and centered relative to this seat, 13, the bottom surface of the master-plate and the upper 70 surface of the disk laid thereon will be parallel to each other. The combined thickness is therefore substantially uniform. In Fig. 1, at the left-hand side, I have shown a buckled disk centered upon the master-plate, 75 12, in cross section. The master-plate with the disk applied thereto is then passed through a set of rolls, 14, the lower rolls of the set being driven while a yielding pressure is applied to each of the upper rolls. 80 These rolls are staggered with reference to each other, as shown in Fig. 1, and cause the flexing of the disk and master-plate as they pass through the set of rolls. Such a machine is commonly known as a straightening 85

machine. At the right-hand side of Fig. 1, I have shown, in cross section, the master-plate, 12, with the disk, 10, applied thereto, as they come from the set of rolls, 14, and it will be noticed that the buckles, 11, have 90 been completely eliminated so that the upper surface of the disk, 10, and the lower surface of the master-plate, 12, are parallel to each other.

In Fig. 4, I have shown in cross section another form of master-plate, 15, which is adapted to straighten two disks at a single 95 operation. This master-plate, 15, has a conical seat, 16, on each surface thereof, said conical seats being complementary to the perfect disk so that when perfect disks are positioned in these seats the exposed surfaces of the disks, 10, are parallel to each other, as shown in Fig. 4. The process of removing the buckles is the same with this 100 master-plate as with the one previously described. A pair of buckled disks, 10, with the master-plate, 16, between them, are passed 105

through the set of rolls, 14, with the result that all buckles in the disks are removed. I believe that the form of master-plate shown in Fig. 4 is to be preferred, not only because it is quicker, since two disks may be treated at once, but also because the disks are subjected to a greater flexing and the buckles seem to be removed more effectively.

In some cases, I pass the disks through these rolls while cold but the same process may be used with disks that are heated. The disks and master-plate may be passed through the rolls one or more times along one or more radii of the disks.

I am aware that this process of straightening tapered disks may be varied considerably without departing from the spirit of my invention and, therefore, I claim my invention broadly, as indicated by the appended claims. Obviously, too, the process may be used to straighten other articles besides wheel disks.

Having thus described my invention, what I claim as new and desire to secure by Letters Patent is:

1. The process of straightening sheet metal articles of varying thickness without altering the thickness thereof which consists in applying to the article a complementary master matrix having such thicknesses as to render uniform the combined thickness of the article and the matrix and thereafter passing the article and the matrix together through a straightening machine.

2. The process of straightening sheet metal articles of varying thickness but intended to have plane surfaces on one side, which consists in interposing between the non-plane surfaces of two such articles, a master matrix plate having surface configurations complementary to the non-plane surfaces of the

articles to be straightened, and thicknesses such that the combined thickness of the articles and the matrix is substantially uniform, and thereafter passing the articles and the matrix together through a straightening machine.

3. The process of straightening flat articles of pliable form but varying thickness which consists in applying to the irregular face of an article a matrix having a complementary face and passing the article and the matrix together through straightening rolls which straighten by bending without change of thickness.

4. The process of straightening flat articles of pliable material having non-plane surfaces which consists in applying to the non-plane surface a matrix of complementary form and thereafter subjecting the article and the matrix so placed together to rolling without changing the aggregate thickness of the sections.

5. The process of straightening articles of pliable material having non-plane surfaces which consists in applying to the non-plane surfaces a matrix also pliable and of a form complementary to the non-plane surface, and thereafter subjecting said article and matrix to bending in alternate directions beyond the elastic limit of the material.

6. The process of straightening finished articles of irregular surface configuration and which have become buckled or bent which consists in seating the article upon a master matrix having a surface configuration complementary to the surface configuration of the finished article and thereafter forcing the said complementary surface configurations into registry.

In testimony whereof, I affix my signature,
EDWARD G. BUDD.
